UNITED STATES PATENT OFFICE.

WILLIAM P. HAMMOND, OF MAPLEWOOD, NEW JERSEY.

DESIGN FOR A COMBINATION MIRRORSCOPE, PARKING LIGHT, AND DIRECTION INDICATOR.

61,195.

Specification for Design.

Patented July 11, 1922.

Application filed May 11, 1921. Serial No. 468,690. Term of patent 14 years.

To all whom it may concern:

Be it known that I, WILLIAM P. HAMMOND, a citizen of the United States, residing in Maplewood, in the county of Orange and State of New Jersey, have invented a new, original, and ornamental Design for a Combination Mirrorscope, Parking Light, and Direction Indicator, of which the following is a specification, reference being had to the accompanying drawing, forming a part thereof.

Figure 1 is a front plan view of the device, embodying my new design, showing the silvered surface, which acts as a rear view mirror, and the red annular outer zone,

which acts as the parking and rear signal when used as a parking light, and the outwardly extending signal symbol, which acts as a direction indicator.

Figure 2 is a rear view of the device, showing the parking light bull's eye, and the complementary, outwardly extending, direction indicating symbol, which indicates to the traffic officer an intended turn.

I claim:

The ornamental design for a combination mirrorscope, parking light, and direction indicator, as shown and described.

WILLIAM P. HAMMOND.
